CLAIM

The ornamental design for a finger ring tag, as shown and described.

DESCRIPTION

FIG. 1 is a perspective view of a finger ring tag showing our new design;

FIG. 2 is a front elevational view thereof;

FIG. 3 is a rear elevational view thereof;

FIG. 4 is a side elevational view thereof looking from the right with respect to FIG. 1;

FIG. 5 is a side elevational view thereof looking from the left with respect to FIG. 1;

FIG. 6 is a top plan view thereof; and

FIG. 7 is a bottom plan view thereof.

The broken lines showing are for illustrative purposes only and form no part of the claimed design.
